LOCK

Filed Feb. 29, 1928 *Fig. 2*

Inventor:
Theodor Kromer

UNITED STATES PATENT OFFICE

THEODOR KROMER, OF FREIBURG, GERMANY, ASSIGNOR TO THEODOR KROMER GESELLSCHAFT MIT BESCHRÄNKTER HAFTUNG, OF FREIBURG, IN BREISGAU, GERMANY

LOCK

Application filed February 29, 1928, Serial No. 258,074, and in Germany June 7, 1927.

This invention relates to a lock of the kind wherein a lock bolt is normally blocked by a tumbler which is supported by a plurality of locking discs and which drops into aligned notches in said discs for releasing the bolt, the discs being adjusted individually by means of a spindle which is arranged to slide and rotate in the lock casing.

The object of the invention is to provide means necessitating a disarrangement of the discs before the lock is completely opened, and the invention consists essentially in the provision of two tumblers one of which is adapted to retain the bolt partly shot until a disarrangement of the discs has taken place.

For setting the discs, one of them is permanently coupled to the spindle for rotary movement and is provided with a raised toothed rim engaged by a spring-controlled pin.

Fig. 1 of the accompanying drawings represents a sectional view of the lock taken on the line A—B of Fig. 2 and shewing the elements in locking position,

Fig. 2, a side view of the mechanism, also shewing the elements in locking position,

Fig. 3 is another view like Fig. 1, shewing the elements operated for unlocking,

Fig. 4 is another side view of the mechanism, partly in section,

Fig. 5 is a sectional side view of part of the lock mechanism, and

Fig. 6 is a diagram of the top view of the lock.

The lock casing 1 is fitted with a lock bolt 22 which is retained in shot position by abutment against the end 10 of the tumbler 5 which is supported by means of a semi-circular lug 14 on three locking discs 2, 3 and

4. A pivot pin 6 on the tumbler engages in an elongated slot 7 of the casing 1 which allows the tumbler to be lifted together with the pin. A pin 9, which is guided in a slot in the tumbler and controlled by a spring 8,

bears against the casing 1 and holds the tumbler in engagement with the locking discs.

Each locking disc is adapted for rotary adjustment on a setting disc 27 whereby it is mounted on a spindle 24. The setting discs

are toothed for engagement with pins 29

which are mounted in the locking discs and which enable the latter to be retained in different positions relative to the setting discs in order to change the combination of the lock. The pins 29 are controlled by springs 55 28. Each locking disc is provided with a notch 15 into which the lug 14 is adapted to drop so as to release the bolt 22. This can only take place when the notches of all the discs are in alignment. There is a second 60 tumbler 13 which is pivoted at 11 and which rests by means of a lug 20 on the locking disc 4. That portion of the latter which supports the tumbler 13 is reduced eccentrically, as shewn at 36 in Fig. 4, in the region of 65 the notch 15. A flange 12 at the free end of the tumbler 13 extends over the tumbler 5 and forms a second abutment for the bolt 22 after the latter has passed through a fork 34 at the end 10 of the tumbler 5.

The spindle 24 which is slidable and rotatable relative to the casing 1 as well as to the setting discs 27, is used for adjusting the locking discs. For this purpose it is fitted with two pins 25 controlled by springs 33 for engagement with which the discs 3 and 4 are provided with notches 26 and disc 2 with a shoulder 35. The disc aperture 37 is widened helically at one side of the shoulder 35 so that driving engagement only takes place on a right hand rotation of the spindle. The centre disc 27 has merely a notch in which one of the pins 25 engages when the other one is thrown, by an axial movement of the spindle, into co-operation with the respective outermost disc. Thus the centre disc will always be coupled to the spindle, and its locking disc 3 will participate in the rotary movement thereof. A toothed rim 17 which rises beyond the normal periphery of the disc 3, is engaged by a bevelled pin 19 which is controlled by spring 18 and serves as a stop for the locking disc. The lug 14 of the tumbler 5 has a recess 16 wherein the rim 17 can move without affecting the movements of the tumbler.

The spindle is fitted with an operating knob 23 and with a dial 30 whereby it is adjusted relative to an index ring 31 on the door frame. The lock bolt 22 engages nor-

mally in a staple or striking plate 38 and is operated by means of a handle 21 or any other suitable element.

The action is as follows:

5 The lock bolt 22 is normally retained by the tumbler 5 which is supported in operative position by one or more of the locking discs. In order to release the bolt, the locking discs must be adjusted in accordance 10 with the prevailing combination. For this purpose the spindle 24 is first pushed back for engagement with the locking disc 4 and then turned to the right until the dial 30 registers with the setting for this disc. The 15 disc 3 participates in the rotary movement and the pin 19 engages the teeth of rim 17 and retains the disc 3 in its position. Then the spindle is pulled out for engagement with the disc 2 which is similarly adjusted with 20 reference to the dial. Thereupon the handle, without further axial adjustment of the same, is turned to the left for setting the disc 3, this being also effected with reference to the dial. The notches 15 of the locking discs 25 will now be in alignment with one another opposite the lug 14 of the tumbler 5, and the latter will therefore drop so as to allow the bolt 22 to be passed in the direction of the arrow 32 through the fork 34 of the tumbler. 30 However, the bolt will still be blocked by the flange 12 of the tumbler 13 which bears against the reduced portion 36 of the disc 4. In order to free the bolt entirely, the disc 4 must be turned for which purpose the spindle 35 24 is again pushed into engagement with this disc and turned to the right so as to raise the flange 12 and enable the bolt to pass in between the latter and the tumbler 5 for complete retraction. In this operation the 40 tumbler 5, which is engaged by the bolt 22, will be deflected about the fork 34 in opposition to the spring-controlled pin 9.

The second operation of the spindle will have the effect of throwing the locking discs 45 out of order before the lock is completely open, and a risk of leaving the lock in open position will thus be eliminated.

I claim:

1. A lock comprising a casing, a spindle 50 slidably and rotatably mounted in said casing, a plurality of locking discs mounted on the spindle, means on said spindle for setting said locking discs each disc having a peripheral notch, a principal, spring-controlled 55 tumbler guided vertically in the casing, a rounded lug on said tumbler supporting the latter on the locking discs and adapted to drop into the notches thereof when said notches are in alignment, means on the 60 spindle for turning the different discs so as to bring the notches into alignment under the lug, a lock bolt arranged so as to be normally blocked in shot position by abutment against the end of said tumbler and so as to be released on the tumbler dropping into the disc 65

notches, and an additional tumbler supported on an eccentric portion of one of the discs and adapted to prevent the complete withdrawal of the bolt until said latter disc has been turned from the position in which its notch registers with the lug of the principal tumbler. 70

2. A lock bolt comprising a casing, a spindle slidably and rotatably mounted in said casing, a plurality of locking discs mounted on the spindle, each disc having a peripheral notch, a spring-controlled tumbler guided vertically in the casing, a lug on said tumbler supporting the latter on the locking discs and adapted to drop into the notches thereof when said notches are in alignment, means on the spindle for turning the different discs so as to bring the notches into alignment under the lug, a lock bolt arranged so as to be normally locked in shot position by 80 abutment against the end of said tumbler and so as to be released on the tumbler dropping into the disc notches, one of the locking discs being permanently coupled to the spindle for rotary movement, a raised toothed 85 rim on said latter disc, the tumbler lug having a recess in which said rim is accommodated, and a spring-pressed pin co-operating with the teeth of said rim for holding the disc. 90
